Patented Apr. 2, 1912.

UNITED STATES PATENT OFFICE.

EDWARD BLOUNT WINTERS, OF COFFEYVILLE, KANSAS.

GARTER.

1,022,217.

Specification of Letters Patent.

Patented Apr. 2, 1912.

Application filed April 4, 1911. Serial No. 618,806.

To all whom it may concern:

Be it known that I, EDWARD B. WINTERS, a citizen of the United States, and a resident of Coffeyville, in the county of Montgomery and State of Kansas, have invented 5 a new and Improved Garter, of which the following is a full, clear, and exact description.

My invention relates generally to garters 10 and more particularly it is directed to a garter in which the usual resilient strap or band is dispensed with, such resiliency being provided by separate means carried by the garter.

15 The object of my invention is to provide a garter having the usual leg band and clasp, together with a resilient member whereby the garter may position itself when in use, this resilient member being designed 20 to perform the function usually accomplished by making the leg band of rubber.

A further object of my invention is to provide a structure which shall be effective 25 in its operation and by reason of the fact that the leg band is made of unyielding material the life of the garter is materially increased.

30 A further object of my invention is to provide a garter having a distinct resilient means embodied therein whereby the garter when in use may freely position itself, thereby rendering it efficient, the construction being such that it may also be produced at a low figure.

35 Reference is to be had to the accompanying drawings forming a part of this specification in which like characters of reference denote corresponding parts in all the views, and in which—

40 Figure 1 is a perspective view showing my garter in use; Fig. 2 is a partial plan view of the resilient member and the clasp bearing on the rest member; Fig. 3 is a vertical sectional view on the line 3—3 of 45 Fig. 2.

45 My garter is made up of the leg band 1 having one end thereof attached to the resilient member 2 at 3, the other end of the band being provided with a hook 4 also in 50 engagement with the resilient member 2, the band being provided with a clasp 5 whereby the length of the band may be varied in order to adapt it for use on different persons.

55 The resilient member 2 is preferably made of a single piece of wire bent at a

central portion to form a helical spring 6, the ends of the wire being extended preferably parallel to each other whereby arms 7 and 8 are formed, the ends of these arms being offset as at 9, 10, in order to provide hooks whereby the leg band may be engaged therewith. 60

The rest member 11 is designed to bear against the skin of the person using the 65 garter and is preferably made of the conformation shown, the lower end of the member being turned back upon itself as at 12 and fastened to the main body portion by any means such as an eyelet 13, this 70 turned over portion providing a suitable attaching means for a stocking clasp 14. The eyelet 13 or other fastening means, in addition to the supporting clasp 14, also serves as an attaching means for the resili- 75 ent member 2, as shown in Fig. 2, the resili- ent member being positioned between the clasp and the eyelet.

The leg band 1 may be made of any suitable material, the purpose of the invention 80 being to provide a garter in which this material may be non-elastic; the resilient function of the average garter which is supplied by making the leg band 1 usually of rubber is provided in this case by the resilient 85 member 2 so that during motion of the person using the same this resilient member will provide a simple and effective means whereby the length of the garter may be varied to meet the varying movements of 90 the leg.

By making the leg band 1 of non-resilient material I am enabled to provide a garter which will last a great while by reason of the fact that the resilient material 95 used in the average garter is under a constant strain and thereby becomes permanently elongated. The resilient member 2 being made preferably of metal will last an indefinite time and by using the rest 11, 100 this portion is kept out of contact with the skin, thereby providing against destruction by perspiration.

While I have shown my garter of a particular form and the resilient member of a 105 single shape, it will be obvious that various changes may be made in the form, shape, and size of the parts in order to adapt it to different persons without departing from the spirit of the invention as set forth in 110 the following claim.

Having thus described my invention, I

claim as new, and desire to secure by Letters Patent:—

A garter comprising a non-resilient leg band, a resilient member made of a single length of wire and having hooked ends adapted for engagement with the ends of the said leg band, a rest adapted to bear against the leg when the garter is in use, the lower end of the rest being turned back 5 on itself, a clasp engaging the said turned back portion of the rest, the intermediate portion of the said resilient member also 10 engaging the said turned back portion, and

means for securing the turned back portion to the rest, whereby the said resilient member and clasp will be secured to the rest, the resilient member being held from contact with the leg by reason of the rest.

In testimony whereof I have signed my name to this specification in the presence 15 of two subscribing witnesses.

EDWARD BLOUNT WINTERS.
